BUTCHER BLOCK

Emil M. Sprich, St. Louis, Mo.

Application June 13, 1935, Serial No. 26,411

1 Claim. (Cl. 146—215)

My invention relates to butcher blocks, of the kind generally used in butcher shops, and upon which blocks the meat-cutting, chopping, sawing, etc., is done, and has among its objects the production of such a block that will be simple in construction, neat in appearance, sanitary, economical, and otherwise satisfactory and efficient for use wherever deemed applicable.

The common type of butcher block wears down 10 more or less rapidly, dependent upon the amount of work done thereon and the skill and care with which the same is performed, and the usual practice has been to saw, chop or otherwise dress the resultant uneven working surface down to a new 15 level surface, and it is apparent that after a certain number of such re-surfacings the block is too low for safe or economical meat-cutting operations thereon, and hence must be discarded altogether. These re-surfacing operations, and the 20 final discarding of the block, are relatively expensive, and in those cases where the discarding is deferred too long the loss in efficiency of working on such blocks is great.

My invention has among its objects the production of a block of the kind described, wherein 25 the effective working surface, upon which the cutting and chopping operations are performed by the butcher, does not extend the full height or thickness of the block, but for only a minor 30 fraction of such thickness, and hence this relatively expensive portion not only reduces the initial cost of the block, but permits of replacements from time to time at a minimum of expense.

Another object of my invention is to provide 35 a butcher block having a working surface that may be replaced quickly, easily, and at a minimum of expense, and wherein the working height of the block can be substantially maintained indefinitely.

A further object of the invention is to provide such a block wherein not only the height, but the weight and work surface dimensions may be retained fixed for the full life or use of the block, 45 and hence wherein the value of the block will remain substantially constant insofar as utility and efficiency is concerned.

A still further object of the invention is to provide a replacement top for a cutting block, of 50 either the same or a different sized working area, as preferred, at a reduced cost.

An added object of my invention is to provide 55 a replaceable work top for a block, the same to be held in place by substantially its own weight and without the use of tension bolts or the like,

and which may be lifted from its assembled position through jack means operable from beneath the base of the block.

Other objects of the invention are to provide a block construction of the kind described, where- 5 in the force of the cutting or chopping will be suitably absorbed through the same, without undue noise, or other objectionable features.

Many other objects of the construction shown, 10 and the method of performing the same, will be 10 obvious to those skilled in the art to which this invention appertains, from the disclosures herein given.

To this end, my invention consists in the novel 15 construction, arrangement and combination of parts herein shown and described, and the method of forming the block, as will be more particu- 15 larly pointed out in the claim.

In the drawing, wherein like reference char- 20 acters indicate like or corresponding parts throughout the views,

Figure 1 illustrates an old block about ready 20 for discarding; and

Figure 2 is a cross-sectional view through a 25 re-built block according to my invention.

Referring more particularly to the drawing, 30 wherein I have illustrated one of the preferred embodiments of my invention, there is shown an old meat-chopping or butcher block, shown ap- proximately rectangular in working surface for 30 the sake of convenience and because most of the blocks now in use are of that design, the main body or base portion 1 being of suitable wood, such as maple for example, and built up of a number of layers or laminations having through bolts 2 or 35 the like for holding them tightly together to prevent warping or otherwise become shifted from their predetermined relationship. These 40 laminations are usually arranged on end, so that the uppermost or work surface is cut across the grain of the wood, for well known reasons. The 45 legs 3 are secured to the block body to raise the block to the desired working height.

As these blocks become worn they are sawed, 50 cut, or otherwise worked on to present a new 45 plane or level working surface, but it is apparent that after a time it is impractical to cut more material from the top because it is too close to the through bolts 2. Further, by that time, the 55 height of the block will be such that it is no longer safe or efficient to use, because not only will there be danger to the tools and operator when working at such a low table, but the work performed under these conditions is very unsatisfactory in quality and cost. Heretofore, the only 55

thing that could be done was to discard the old block and obtain a new one. The new ones, on the other hand, were made purposely higher than needed or desired, so as to provide for a maximum number of re-dressing operations, and hence the new blocks were not truly efficient until after a few re-dressings.

In my improved construction, in the construction shown, I prefer to use the old block as a foundation from which the new block is formed, the top surface of the old block being first leveled as shown in Fig. 2. Upon the old block is positioned a slab member 4 of relatively heavy thickness, and preferably of wood, but not necessarily laminated, and thereby the cost of the same is relatively inexpensive. Superimposed on this filler slab is the work slab member 5, the latter being of high-grade material and construction, so as to withstand the usage to which it is to be put, and hence may be made of a good grade of maple or the like, the sections or laminations standing on end, and with their uppermost ends cut across the grain of the wood. The thickness of this slab 5 may be less than that of the slab 4. The filler slab 4 may be prevented against lateral shifting relatively of the base or main block 1, by dowels 6 placed therebetween, and the work slab 5 may be similarly prevented against lateral displacement by means of dowels 7. A band or tie 8 may be secured about the sections of the top plate 5 to clamp them together into a unitary element, this band being preferably of metal.

Although the slabs 4 and 5 are relatively heavy, so as to be able to withstand the service to which they are subjected, yet for the purpose of giving additional weight, and of still better holding said slabs in place, I have provided an apron member having an inwardly directed substantially horizontal flange 9 resting on the top surface 40 of the base element, about the periphery of the latter, said apron member having another portion directed downwardly therefrom at 10 and an oppositely directed portion 11. The portion 10 snugly encircles the peripheral surface of the base member 1, while the other portion 11 similarly encircles the peripheral surface of the filler slab and substantially half of that of the work slab. The filler slab is provided with a cut-out or shoulder 12 on its under side and along its 50 periphery to receive the flange 9, while the upper edge of the portion 11 may be provided with a cut-out or shoulder 13 to receive the band 8.

The use of the apron member of the size shown will permit of the use of a top slab of larger effective working area than the top of the original block 1, and hence this excess working area is obtainable at substantially no increased cost.

The thickness of the work slab is such that it may be dressed down once or twice if so desired, and then replaced with an entirely new slab, or thus replaced without any dressing whatsoever, inasmuch as the costs of such replacements are relatively low. Thus, the original height of the block as shown in Fig. 2 may be retained for indefinite periods, so that the maximum safety and operating efficiency of the block may be preserved.

In order to conveniently displace the work slab, for dressing or replacement, I have provided a simple jack means 14 therefor, the same extending centrally through the base or body portion 1 and having an enlarged top or head 15 fitting within an opening 16 on the under side of the 15 filler slab. As the jack is operated, as by a socket wrench or the like, from beneath the block, the pair of slabs will be lifted in unison to the desired height, the dowels acting as guides during this vertical movement, after which the top slab may 20 be handled as desired.

Obviously, by the construction hereinbefore shown and described, the resultant block will be such that the height can be retained indefinitely, and wherein all of the parts except the relatively 25 thin work top will retain the fixed height, weight dimensions and value, as there is no destruction due to wear, except the small amount at the work top and which can be corrected by replacements at small cost.

Having thus described my invention, it is obvious that various immaterial modifications may be made in the same without departing from the spirit of my invention; hence I do not wish to be understood as limiting myself to the exact 35 form, arrangement, combination and construction, or the method used, except as limited by the state of the art to which this invention appertains or the claim hereunto appended.

What I claim as new and desire to secure by 40 Letters Patent is:

The combination with a butcher block provided with a top surface, of a detachable top member therefor comprising independently movable upper and lower layers freely supported as a unit 45 on said block, a flange peripherally about the top of said block and projecting above and below thereat, said top member being received as a unit within said flange so as to project thereabove and being vertically movable as a unit past the top 50 of said flange while the latter remains in place on the block, and means operable from beneath said block free of securement with said upper and lower layers of said top to lift said top as a unit.

EMIL M. SPRICH.
